CLAIM

The ornamental design for a hitch step, as shown and described.

DESCRIPTION

FIG. 1 is a top perspective view of a hitch step showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a hitch step showing our new design; and,

FIG. 10 is a bottom perspective view thereof.

In the drawings the broken lines depict portions of the hitch step that form no part of the claimed design.
